SUPERHETERODYNE RECEIVER

Dudley E. Foster, South Orange, N. J., and Charles W. Finnigan, Forest Hills, Long Island, N. Y., assignors to Radio Corporation of America, a corporation of Delaware

Application January 4, 1938, Serial No. 183,244

2 Claims. (Cl. 250—20)

Our present invention relates to signal receiving systems, and more particularly to receiving systems of the superheterodyne receiver type employing a local oscillator constructed to have substantial frequency stability.

In receiving systems of the type employing automatic volume control (AVC hereinafter) it has been observed that the action of the control circuit causes a fluctuation in plate voltages supplied to tubes not under control. This may be ascribed to the fact that the AVC circuit functions to change the plate current flowing through the controlled signal transmission tubes, and thereby changes the value of the direct current voltage fed from the receiver power supply circuit to other circuits of the receiver. For example, in a superheterodyne receiver employed in the short wave band of 4 to 22 megacycles (mc.), the AVC circuit will act to cause the local oscillator to drift from its adjusted operating frequency. In a receiver of this type a change in the plate potential of the local oscillator tube will cause a substantial change in the frequency of the oscillator network. At the high frequencies employed in the 6-22 mc. range, a considerable change in the oscillator frequency will cause the I. F. value to depart to an extent such that the desired signal carrier will be lost.

Accordingly, it may be stated that it is one of the main objects of our present invention to provide a method of receiving modulated signals while employing an AVC circuit; the receiving system employing the superheterodyne method of reception by utilizing a local oscillator network which is constructed and arranged to have its established operating frequency independent of variations in the plate potential of the oscillator tube, and which variations may be caused by the action of the AVC circuit.

Another important object of the invention is to provide an oscillator network which has its input and output circuits constructed and arranged to render the operating frequency of the network substantially independent of variations of the plate potential of the oscillator tube; the circuits employed in the network being such that when the plate potential varies opposed frequency variation tendencies render the oscillator frequency substantially independent of the plate potential variation.

Another object of our invention is to provide a superheterodyne receiver of the type employed to receive frequencies of the order of 0.5-22.0 mc., and which receiver also utilizes an AVC circuit; the receiver having its local oscillator designed

in such a manner that plate potential variation of the local oscillator tube caused by the AVC action results in opposed frequency changes in the local oscillator network with the result that the operating frequency of the oscillator is substantially independent of the plate potential variation.

Still other objects of our present invention is to improve generally the efficiency and reliability of oscillator circuits of superheterodyne receivers, and more especially to provide such circuits so that they are not only durable and reliable in operation, but are economically manufactured and assembled.

The novel features which we believe to be characteristic of our invention are set forth in particularity in the appended claims; the invention itself, however, as to both its organization and method of operation will best be understood by reference to the following description taken in connection with the drawing in which we have indicated diagrammatically a circuit organization whereby our invention may be carried into effect.

In the drawing:

Fig. 1 schematically shows a superheterodyne receiver embodying the present invention.

Fig. 2 graphically illustrates the characteristic of the local oscillator network employed in the circuit of Fig. 1.

Referring now to Fig. 1, it will be observed that the receiving system shown is of the superheterodyne type, and it is to be understood that the networks thereof, with the exception of the present invention, may be purely conventional in construction. For example, the receiver can be of the multi-range type so that it can be used to receive signals in the broadcast band of 500 to 1500 k. c. and it can also be used to receive signals in the short wave range of the order of 0.5-22 mc. The various circuit elements enabling the receiver to be changed from the broadcast band to the short wave range have not been shown, since those skilled in the art are fully aware of the nature of such circuit elements. For the purpose of the present application let it be assumed that the receiving circuit in Fig. 1 is arranged to receive signals in the aforementioned short wave range. The signal collector 1 may be of any desired construction; it may be a grounded antenna circuit; a radio frequency distribution line; a loop collector, or a collector device usually employed on mobile structures such as automobiles.

The signal collector feeds the collected signals to a radio frequency amplifier network 2, and

the latter may comprise one or more stages of radio frequency amplification. The amplified signals are fed to a first detector network 3, and the latter customarily employs a turnable 5 input circuit. The numeral 4 denotes the variable tuning condenser which is usually employed to tune the input circuit of the radio frequency amplifiers and the first detector to a common signal carrier frequency; it will be understood 10 that the numeral 4 denotes, in schematic fashion, the gang of variable tuning condensers disposed in such tunable input circuits. The first detector network has impressed thereon, in any suitable manner, locally produced oscillations from a local 15 oscillator network comprising tube 5.

The latter tube includes a control grid 6, a cathode 7 and a plate 8. The tank circuit of the oscillator includes a coil 9 which has connected in shunt therewith a variable condenser 10. The 20 rotors of variable condenser 10 are arranged for mechanical uni-control adjustment with the rotors of the variable tuning condensers 4, and the broken lines 11 designate such uni-control tuning device. Of course, in actual practice the 25 variable condensers 4 and 10 will be part of a common gang of condensers; such construction is too well known to require any further description. The high potential end of coil 9 is connected to plate 8 through a condenser 11, the 30 junction of the low potential terminals of coil 9 and condenser 10 being established at ground potential.

The cathode 7 is connected to a suitable tap 35 12 on coil 9, and the control grid 6 is reactively coupled to coil 9 through a path which includes the condenser 13 and the small tickler coil 14. The leak resistor 15 is connected between the grid side of condenser 13 and the cathode lead of tube 5. Coil 14 is magnetically coupled to coil 40 9; if desired, coils 9 and 14 may be a common coil with taps 12 and 16 provided thereon to provide the required tank and feedback coil sections. The frequency of tank circuit 9-10 is adjusted at all times to differ from the signal frequency 45 of the tunable signal circuits by a frequency equal to the operating I. F. The I. F. may have a value of substantially 460 kc., assuming that the signal is operating in a signal range of 0.5 to 22 mc. The I. F. output of the first detector 50 network 3 is impressed upon an I. F. amplifier 17, and it will be understood that the network 17 may include one or more stages of I. F. amplification and that the I. F. amplifier tubes will have input 55 and output circuits each tuned to the operating I. F. value.

The amplified I. F. energy is impressed upon a demodulator, or second detector, network 18, and the audio output of the demodulated I. F. energy is impressed upon one or more stages of audio 60 frequency amplification, followed by an audio reproducer. The numeral 20 denotes the receiver power supply network, and the latter is schematically represented since those skilled in the art are fully aware of its construction. The receiver power supply network is shown arranged to feed 65 direct current to the plate circuit of the oscillator tube 5, and it will be understood that the plate 8 of the oscillator tube is connected to a point of proper positive potential on the power 70 supply bleeder resistor through the resistor 21. The lead 22 denotes the direct current voltage connections from the supply network 20 to the various plate circuits of the networks 2, 3, 17 and 18. Of course, the supply network 20 usually 75 comprises, if an A. C. source is used, a rectifier

followed by a filter circuit, and a direct current voltage supply bleeder resistor being connected across the filter circuit output. The various connections 22 and 21 are usually made to a common direct current voltage supply bleeder resistor; a change in potential at the plates of tubes used in networks 2, 3 and 17 will cause a change in the potential of plate 8 of tube 5. Such plate potential variations will occur, for example, when 10 AVC is utilized to minimize "fading" effects. 15

Effects other than AVC action may cause the plate potential of oscillator 5 to vary; these are variation of line voltage, and fluctuations due to variation of the plate current of the power tube during the audio frequency cycle. The 20 source of all direct current potential is the rectifier tube; the rectifier itself, filter chokes, speaker fields etc., all, having some resistance, are interposed between the voltage source and the amplifier and oscillator tubes. This resistance may be 25 as little as 500 ohms, but is usually larger and may be much greater in some circuits. Change of the voltage drop across such resistance occurs when the amplifier tube current (or power tube current at A. F.) varies, producing corresponding changes in the plate potential of the oscillator. 25

The AVC circuit employed herein is conventional in nature; it is schematically represented by the lead 30 (denoted AVC) connected between the signal grid circuits of the tubes used in the 30 network 2 (the tubes of networks 3 and 17 may also be controlled) and the rectifier 31. The I. F. energy may be impressed on rectifier 31, and the direct current voltage output thereof is employed to decrease the gain of each of the controlled 35 tubes as the carrier amplitude increases. The AVC circuit acts to decrease the gain of the controlled tubes in a manner such that the I. F. carrier amplitude at the input of network 18 is substantially uniform, regardless of a wide variation of carrier amplitude at the collector 1. The 40 numeral 32 denotes a filter element, such as a resistor-condenser network, for suppressing pulsating components in the AVC bias. The action of the AVC is well known; for weak signal reception the gain of each controlled tube, hence the space current flow thereof, is a maximum. As the carrier amplitude increases, the AVC bias acts to reduce the gain of each tube; the space current flow thus decreases. 45

The potential of the plate 8 of oscillator tube 5 will fluctuate in a fairly substantial manner because of the variation in space current flow in the controlled tubes, and which variations are caused by the AVC bias. The variations in plate 55 potential of plate 8 may occur to an extent sufficient to cause the operating frequency of tank circuit 9-10 to vary in a manner such that the desired station is lost. The circuits of the oscillator tube are arranged practically to eliminate the 60 frequency change caused by the oscillator plate potential variation. The circuits of oscillator tube 5 are a combination of the well known Hartley type of oscillator circuit and the equally well known tuned plate circuit oscillator. By 65 combining these types of oscillator circuit arrangements there is secured opposing frequency variation tendencies which result in a substantially constant operating frequency regardless of oscillator plate potential change. 70

The Hartley type of oscillator circuit employs the oscillator tank circuit in both the plate and grid circuits. The curve A in Fig. 2 shows the relation between the frequency drift and plate voltage change for this type of oscillator circuit. 75

It will be observed that the curve A has a falling relation between the frequency and plate voltage increase. In other words, for the Hartley oscillator circuit, as the plate voltage of the oscillator tube plate increases, the operating frequency of the circuit decreases. On the other hand, for the tuned plate oscillator circuit the frequency of the circuit increases as the plate voltage increases. The curve B in Fig. 2 shows the nature of this curve, and it is to be understood that the curve B illustrates the frequency drift-plate voltage variation of an oscillator circuit whose tank circuit is wholly in the plate circuit of the oscillator tube. It will be observed that curves A and B are opposing, and that they nullify their respective effects as the plate voltage increases. The circuits of the oscillator in Fig. 1 are a combination of the two well known circuits, and it will be seen that tank circuit 9-10 is not only in the plate and grid circuits of the oscillator tube, but the control grid 6 is reactively coupled, through coil 14, to the tank circuit. This circuit arrangement results in the production of the effects illustrated by curves A and B in Fig. 2, as the plate voltage of oscillator tube 5 increases.

The receiving circuit, therefore, will not change its operating local oscillation frequency once the variable condenser 10 has been adjusted to a predetermined oscillation frequency. Regardless of how the AVC circuit functions to vary the operating plate potential of oscillator tube 5, the operating frequency of the oscillator circuit will remain substantially independent of the plate potential change. Of course, separate tubes need not be employed for the first detector and oscillator networks (a pentagrid converter tube of the 6A7 type can be employed in place thereof). As stated before, moreover, the present invention is not restricted to overcoming the frequency change effect caused by AVC action; it is of equal value to counteract such frequency change when caused by any variation in the power supply circuit which might otherwise cause the local oscillator frequency to drift from its proper value.

To illustrate the applicability of our invention to the broadcast band, as well as to the short wave range, a coil was constructed in accordance with this invention for use on the broadcast band. The coil was wound on a 1 inch form with No. 30 enamelled wire. Resistor 15 was 50,000 ohms; condenser 13 was 100 mmf. Coil 9 had 77 turns with tap 12 located 65 turns from the ground end. Coil 14 had 18 turns wound adjacent to the grounded end of coil 9. The stability with a type 56 6C5 tube was such that when the plate potential was changed from 250 to 200 volts the shift at 1,000 kc. was only 20 cycles, and at 1,900 kc. 40 cycles.

In our invention the oscillation amplitude need not be limited in an attempt to obtain better frequency stability; as a matter of fact it is usually preferable to choose a cathode tap for the Hartley circuit portion which gives as much oscillator

amplitude as possible in the short wave range. In the broadcast band, the cathode tap providing maximum oscillator amplitude may result in too much oscillator voltage on the first detector, since the conversion efficiency of a first detector suffers if there is too much oscillator amplitude, as well as if there is too little. In any case, the value of oscillator amplitude which gives desirable conversion efficiency of the first detector will cause the frequency of a Hartley type oscillator to shift in the manner shown in Fig. 2. Combining the tuned plate type of coupling therewith does not diminish the amplitude of oscillation, although it does provide the desired frequency stability. It may be seen, therefore, that our invention permits oscillator operation in such a manner that a high degree of frequency stability and a high conversion efficiency of the first detector may be simultaneously achieved.

While we have indicated and described a system for carrying our invention into effect, it will be apparent to one skilled in the art that our invention is by no means limited to the particular organization shown and described, but that many modifications may be made without departing from the scope of our invention, as set forth in the appended claims.

What is claimed is:

1. In a superheterodyne receiver of the type including a signal transmission tube, a local oscillator tube provided with a tunable tank circuit and an automatic volume control circuit arranged to vary the gain of the signal transmission tube; a common power supply circuit connected to said transmission tube and oscillator tube, and circuits electrically connected with said oscillator tube and tank circuit to introduce opposing frequency variations in said tank circuit upon a change of the oscillator tube plate potential caused by the automatic volume control action.

2. In a superheterodyne receiver of the type adapted to operate in a range of frequencies including 0.5 to 22 mc., and which receiver comprises a radio frequency amplifier, first detector and an intermediate frequency amplifier; an automatic volume control circuit adapted to vary the gain of each of the signal transmission stages in response to received signal amplitude variation, a common power supply circuit connected to the various signal transmission stages; a local oscillator tube having its electrodes connected to said common supply circuit, a tunable tank circuit electrically associated with said oscillator tube, the frequency of the tank circuit increasing with plate potential increase of the oscillator tube, said plate potential increase being caused by the AVC action; and means electrically associated with said oscillator tube and tank circuit to provide a frequency variation with increasing oscillator plate potential such that said frequency increase is substantially eliminated.
